PILING FOR THE CONSTRUCTION OF RETAINING WALLS OR THE LIKE

Ronald H. Drawsky, Walnut Creek, and David C. Thomas, Moraga, Calif., assignors to Kaiser Aluminum & Chemical Corporation

Filed June 11, 1974, Ser. No. 478,192

Term of patent 14 years

Int. Cl. D25—01

U.S. Cl. D25—74

FIG. 1

FIG. 2

FIG. 3

FIG. 4

FIG. 1 of the drawings is a perspective view of one embodiment of a piling for the construction of retaining walls or the like embodying our new design;

FIG. 2 is a sectional view taken along line 2-2 of FIG. 1;

FIG. 3 of the drawings is a perspective view of a further embodiment of the piling for the construction of retaining walls or the like embodying our design; and

FIG. 4 is a sectional view taken along line 4-4 of FIG. 3.

We claim:

The ornamental design for a piling for the construction of retaining walls or the like, substantially as shown and described.
